UNITED STATES PATENT OFFICE.

VICTOR PESSEMIER, OF TACOMA, WASHINGTON.

METHOD OF MANUFACTURING SHOES.

Application filed January 26, 1927. Serial No. 163,761.

This invention relates to a method of manufacturing shoes, designed primarily for use in connection with the well known type of McKay stitching machines, but it is to be understood that a method, in accordance with this invention, can be employed in connection with any form of shoe stitching machine for which it is found applicable, and the invention has for its object to provide, 5 in a manner as hereinafter set forth, a new, novel and expeditious method of the class referred to whereby the rear portion of the inner sole, outer sole and upper and the forward portion of the outer sole and upper are stitched together from within the interior of an upper after being lasted and with the last removed, and further with the fore part or portion of the upper maintained in extended, lasted or shaped position during the 10 stitching of the fore part of the upper and outer sole together.

Further objects of the invention are to provide, in a manner as hereinafter set forth, a method for manufacturing shoes and 15 which eliminates the fore part of the inner sole of the shoe, thereby giving the shoe the flexibility of a hand turn at the front and the stamina, rigidity and high arch support at the rear, as is obtainable more particularly in the McKay method or process of manufacturing shoes.

A further object of the invention is to provide, in a manner as hereinafter set forth, a method of manufacturing shoes which 20 provides for a shoe with an unusually satisfactory smooth inside sole on which the foot rests, eliminates tacks which are employed in the McKay process or method, and further eliminates heavy rough seams inside 25 of the completed shoes which are present in the hand turned production of shoes.

Further objects of the invention are to provide, in a manner as hereinafter set forth, a method of manufacturing shoes which is 30 simple in its use, thoroughly efficient, conveniently carried out, and comparatively inexpensive to employ.

With the foregoing and other objects in view, the invention consists of the novel 35 combination and arrangement of steps hereinafter more specifically described in carrying out the method, but it is to be understood that changes, variations and modifications with respect to the steps of the method 40 can be resorted to which fall within the scope of the claim hereunto appended.

The drawing illustrates by way of example, lasting and shape retaining appliances employed in carrying out a method of manufacturing shoes in accordance with this invention. 60

Figure 1 is a perspective view of a last having mounted upon the fore part thereof a shape retaining shell employed in the method. 65

Figure 2 is an inverted plan of a last having mounted thereon or rather lasted thereon an upper indicated in dotted lines and further having mounted thereon a shape retaining shell and an inner sole. 70

Figure 3 is an inverted plan view of a last having secured thereon an upper, a shape retaining shell, an inner sole and an outer sole and with the latter detachably secured to the last. 75

Figure 4 is a section on line 4—4 Figure 3.

Figure 5 is a transverse sectional view of the completed fore part of the shoe. 80

Figure 6 is a section on line 6—6 Figure 3.

Referring to the drawings in detail 1 denotes a last preferably of the ordinary McKay type and which has connected to the fore part or front portion thereof a shell 2 of rigid material. The shell 2 conforms to the exact measurement of the forward part 85 or front portion of the last 1 and snugly embraces the same. The shell 2 is termed a shape retainer and is open at its bottom and further is inturned throughout its bottom to form a gripping flange 3 of appropriate 90 width. The material from which the shell 2 is constructed is of the desired thickness. The shell 2 completely encloses the top, sides and toe portion of the last 1 at the front portion of the latter. 95

An inner sole is indicated at 4 and the fore part 5 thereof has its edge throughout inset with respect to the sides and toe at the front portion of the last 1. The inset edge of the fore part 5, of the inner sole 4, 100 is indicated at 6 and which provides a pair of shoulders 7. When the shell 2 is mounted in position the ends of the flange 3 abut against the shoulders 7. The rear part of the inner sole 4 is indicated at 8 and which 105 is flush with the sides and heel of the last 1. The inner sole 4 is detachably secured to the bottom of the last 1 in a known manner.

The upper of the shoe is generally indicated at 9 and which is drawn over the last, 110 with the shell attached, and tacked or stapled to the inner sole in the ordinary McKay

lasting manner and the staples or tacks for attaching the upper 9 in lasted position are indicated at 10. The staples or tacks do not extend through the flange 3 of the shell 2, but are spaced inwardly with respect thereto. The flange 3 is spaced from the edge 6.

The outer sole is indicated at 11 and is detachably secured, as at 12, to the inner sole and which encloses the inturned attached portions 13 of the upper 9.

After the elements of the shoe, that is to say the inner sole 4, upper 9 and outer sole 11 are positioned in a manner as aforesaid, the last 1 is pulled out, leaving the shell 2 in the forepart of the shoe thereby retaining its shape. In order that the shell will remain in its exact position, the flange 3 thereof abuts against the shoulders 7. After the last has been removed, the arm or horn of the McKay stitcher is inserted within the upper and the inner sole, upper and outer sole are stitched together as at 15, within the area designated A, B and C. After the inner sole, upper and outer soles are secured together, at what may be termed the rear part thereof, the upper and outer sole, from within the upper, are stitched together, as at 16, within the area designated D, E and F, or in other words the fore part of the upper and outer sole are stitched together from within the upper and such stitching is guided by the inset edge 6 of the fore part of the inner sole 4. When the fore part of the outer sole and upper are secured together, the stitching is free of the flange 3. After the fore part of the outer sole and upper are stitched together, the shell 2 is then removed, the fore part 5 of the inner sole cut off at the point designated X, the

upper is disconnected from said fore part 40 5 and the latter is then removed and the shoe is complete.

To eliminate roughness on the inside fore part of a completed shoe, the outer sole is rabbeted as at 14 to make a flush edge with 45 the stitched upper.

It is thought the many advantages of a method of manufacturing shoes, in accordance with this invention, can be readily understood, and although the preferred embodiment of the invention is as illustrated and referred to, yet it is to be understood that changes, variations and modifications of the steps of the method can be had which will fall within the scope of the invention 55 as claimed.

What I claim is:

A method of manufacturing shoes comprising detachably securing to the bottom of a last of an inner sole having the edge of the fore part thereof inset with respect to the edge of the rear part thereof, removably positioning a shape retainer throughout the fore part of the last and with the edge thereof of opposing said inset edge throughout, lasting an upper in position, detachably securing an outer sole to the inner sole and against the upper, removing the last, stitching the rear part of the inner sole, upper and outer sole together, stitching the fore part of the outer sole and fore part of the upper together while guided by said inset edge, and then removing said retainer and fore part of the inner sole. 65 70 75

In testimony whereof, I affix my signature hereto.

VICTOR PESSEMIER.
